LOOP CONTROLLED VARIABLE-SPEED
DRIVEDonald A. Cumfer, Elmhurst, Ill., assignor to
United States Gypsum Company, Chicago, Ill.,
a corporation of Illinois

Application June 1, 1945, Serial No. 597,123

4 Claims. (Cl. 271—2.3)

1

This invention relates to apparatus for the continuous processing of web material in connection with which power-driven rolls (draw, feed or pull) are usually employed for moving the web, more particularly to apparatus for maintaining desired conditions of slack or tension in the web between two successive sets of rolls, and it is an object of the invention to provide improved apparatus of the character indicated.

In the processing of web material it has been usual to maintain the peripheral speeds of the draw, feed or pull rolls at substantially the speed necessary to pass the same number of feet per minute through each of the sets of rolls, thereby theoretically to insure that the web will progress at uniform speed throughout the processing range.

However, many factors enter into such processing to cause the web to progress at variable speeds through the processing units irrespective of the maintenance of said feeding rolls at a predetermined speed. Such factors particularly are encountered in the processing of a web of roofing material foundation such as felt. When felt is processed into roofing material, the thickening of the web by progressive saturating, coating and surfacing conduces to such increase of thickness as to interfere with the speed which otherwise would be expected to be maintained at various feeding or drawing rolls. Moreover, webs of all kinds stretch during processing, thereby adding another unpredetermined factor. Finally, one frequent cause of web slippage on feed rolls, with consequent failure of the latter to be able to maintain the progress of the web at predetermined speed, arises from the surface of the web becoming slippery by reason of the processing applied thereto at various points.

It has heretofore been suggested that the variable speeds of the web as it progresses through the processing unit could be regulated to prevent undesirable conditions and/or stresses in the web by utilizing various variable speed changing devices. However, most of these latter are manually operated and require constant attention. This is particularly true when it is desired to maintain tension on a web extending between two feeding or pulling units where each of the units is capable of positively gripping the web as it leaves one unit and enters a succeeding unit. Under the last indicated conditions, if the entering rolls of one unit pull the web faster than it is fed from the last rolls of the preceding unit, the tension on the web will eventually exceed its tensile strength whereupon it will rupture or break.

2

Again, and especially frequently in connection with processing of web materials into roofing materials, it is required to set up a slack loop between two sets of draw, feed or pulling rolls and to maintain the size of this loop between two rather definite dimensional limits. Under these conditions it is exceptionally difficult to insure automatically that the web material will be maintained in a loop of proper dimensions between the two sets of rolls. So far as aware, such slack loops are now maintained between units by employing manually controlled variable speed devices of some kind. These devices encompass the necessity of manual operation and accordingly require that an operator maintain constant vigilance to insure that the slack loop continues within the dimensional limits imposed by the operating exigencies. When the operator notices that the loop is beginning to lose, i. e., that the amount of material in the loop is decreasing, the feed rolls are speeded up whereupon the loop gains material. However, this speed-up causes a continued gain even after the desirable loop dimension is attained. The operator then must again manipulate the controls to retard the speed of the material feeding devices, and in a short time the loop again begins to lose and the entire operational cycle must be repeated. Not only does such manual control require the constant vigilance of a trained operator to insure maintenance of proper operational loop dimensions, but it is also true that these loop dimensions are usually securable only by manipulating some sort of speed-changing devices directly in connection with the feed rolls, which with prior devices introduced a burdensome factor of expense and material.

This last shortcoming is also present in all of the quasi or manual assistance semi-automatic controls which have been proposed in connection with such loop maintenance. However, even with prior devices where the control is effected theoretically automatically the speed changing devices operating in connection with the feed rolls are heavy, involving the use of heavy pulleys or disks connected by belts or chains. Thus, whenever the speed changing device is brought into operation it is necessary to accelerate the heavy masses thereof and after the desired loop dimensions are attained, it is necessary to apply a large braking force to slow down and stop these masses. Consequently, the clutch gripping surface which effects starting of the speed changing mechanism and the braking surface which effects stopping thereof are subject to heavy wear. Furthermore, the parts of the speed changing mechanism directly

connected to the feed rolls stop and start whenever the feed rolls are started and stopped, which may occur frequently, and thus in addition to the load on the clutch and brake mechanisms to start and stop the feed rolls, there is the load of a portion of the speed changing mechanism.

Accordingly it is a further object of the invention to provide improved apparatus of the character indicated that is simple, easy to use, small, and light in weight.

It is a further object of the invention to provide improved apparatus of the character indicated that is completely automatic in operation.

It is a further object of the invention to provide improved apparatus for changing the relative speeds of successive rolls in web or material feeding apparatus.

It is a further object of the invention to provide in material feeding apparatus having a pair of rolls between which material is fed an improved process for varying the material feeding speed of one or both of said rolls.

According to one form of the invention, apparatus for controlling the relative speeds of two adjacent rolls is provided including speed varying means adapted to be driven by one of the rolls, means for driving the other of the rolls from the speed varying means, and means responsive to a condition to be regulated for controlling the speed varying means. More particularly, there is provided in material feeding apparatus having at least two rolls between which material is fed, the combination of means for maintaining a predetermined amount of material between the sets of rolls including means for varying the speed of one of the rolls and a reversible motor for operating the speed varying means. Electrical means responsive to variations in the predetermined amount of material are provided for energizing the reversible motor along with time delay means for delaying changes in the motor energization effected by the responsive means.

For a more complete understanding of the invention reference should now be had to the accompanying drawings, in which:

Fig. 1 is a side-elevational view of winding and looping apparatus embodying the invention;

Fig. 2 is a top plan view of the apparatus shown in Fig. 1;

Fig. 3 is a somewhat enlarged sectional view taken substantially in the direction of the arrows 3—3 of Fig. 2;

Fig. 4 is a somewhat enlarged fragmentary view taken substantially along the line 4—4 of Fig. 2;

Fig. 5 is a wiring diagram of the control system embodied in the invention;

Fig. 6 is an elementary wiring diagram illustrating the manner of operation of the control system; and

Fig. 7 is a sectional elevational view of a relay shown schematically in Fig. 5.

Referring more particularly to the drawings, the invention is shown embodied in web-processing apparatus including a winder 10 and a looper 11.

The looper 11 is a well known piece of apparatus for forming loops 12 of the material being processed and conveying them from the point of formation to the point of utilization. For example, the loops 12 may be of roofing material having a coating of wet substance applied thereto and are being conveyed through a drying oven or treating chamber to the winder 10 for winding on a roll or mandrel. The looper 11 is shown somewhat schematically as comprising a series

of hangers 13 spaced apart a sufficient distance to support loops 12 of material between them, the hangers being supported upwardly from the floor by a suitable framework or guide shown by the line 14. The hangers 13 are moved along the guide 14 by any well known means (not shown) to convey the loops 12 from one end of the looper toward the other. When any loop 12 arrives at the end of its travel, i. e., the plate 15 ending 10 the looper, the particular hanger is held stationary while the material is pulled out of the loop following which another hanger moves into place to have the associated loop of material removed, as is well understood by those skilled in this art, this process continuing as long as desired.

At the end of the looper adjacent the plate 15 there is a framework exemplified by the vertical columns 16 and 17 from which extend the brackets 18 and 19. Supported on the brackets by 20 means of suitable bearings are the looper exit rolls 21 and 22 which feed or pull the web material out of the looper, the lower roll 22 having a sprocket 23 keyed or otherwise attached to its shaft for driving the roll 22. The material is fed 25 between the rolls 21 and 22 and thus the roll 21 is spaced away from the roll 22 a distance so as to exert sufficient force on the material whereby driving only the roll 22 will move the material. Spaced directly behind the exit rolls is an idle 30 guide roll 24 for supporting the web material away from the plate 15 and feeding it to the exit rolls 21 and 22 as it leaves the looper 11.

The construction of the looper 11 is shown schematically since it is exemplary of a variety 35 of forms of apparatus used in processing web materials, the invention having application to any such apparatus including two parts between which it is desired to maintain a slack loop of predetermined dimensions or other condition of the material such as the tension therein. Apparatus of this character commonly has rolls feeding the web material out of one part thereof, and also has rolls feeding the material into the other part thereof. Between these rolls the slack 40 loop or tension, for example, is maintained. As part of the looper 11 the exit rolls 21 and 22 have been shown and described beyond which a slack loop is to be maintained as will become clear as the description proceeds.

The winder 10 is mounted on a framework 20 made of structural members such as I-beams supported on a suitable foundation, the framework 20 also supporting a winder drive mechanism 25.

The winder drive mechanism 25 comprises a motor 26, a speed reduction gear 27 driven by the motor and a pulley 28 through which the winder 10 is driven, the reduction gears being driven by any well known means such as belts 29, for example. The winder 10 includes a frame 31 supporting feed and guide rolls, a mandrel 32 on which the web material is wound, a roller table 33 upon which the roll of wound material is ejected when completed and a synchronizing mechanism 34 for varying the rotative speed between the feed rolls of winder 10 and exit rolls 21 and 22 of looper 11. The winder 10 is mounted on the supporting framework so that the web material comes out of the looper and enters the winder forming a slack loop therebetween, the material being fed directly into the winder. Since the slack loop must necessarily hang down between the looper and the winder an idle guide roll 35 is provided on the framework 20 to guide the material to the winder feed rolls.

The winder frame 31 extends upwardly from

framework 20 so as to support the feed and guide rolls above the latter framework and in a proper position to receive the web material. At the forward end of the winder there is a guide roll 36 over which the web passes as it enters the winder and is provided with circular flanges or guides 37 spaced apart the width of the material being fed so as to guide it and prevent its moving from side to side. The guide roll 36 is mounted in bearings in frame 31 and is not power driven, the weight of the material thereon being sufficient for this purpose. Two pairs of vertically spaced feed rolls are provided and supported in bearings in frame 31, the feed rolls being directly in back of the guide roll 36. The forward pair of feed rolls 38 and 39 and the rearward pair of feed rolls 41 and 42 are positively driven through gears (not shown) from the pulley 43 whereby the web material is firmly gripped and pulled without slipping. Spaced directly behind the rolls 41 and 42 is a table 44 over which the material passes so as to be fed to the mandrel 32 upon which it is wound, the mandrel also being driven through gears (not shown) from the pulley 43. The table 44, the space between feed rolls of each pair thereof and the guide roll 36 are at the same height off of the frame 20 so the web material may feed through the rolls and onto the mandrel substantially in a straight line. Laterally displaced from and in line with mandrel 32 is the roller bed 33 which comprises a series of rollers 45 mounted in a frame so that as the completed roll of material is taken from the mandrel it is rolled away on the rolls 45 in a simple and expeditious fashion.

In order to drive feed rolls 38, 39 and 41, 42, the shaft 46 and the pulleys 47 and 48 mounted thereon are supported in suitable bearings on the upright columns 16 and 17. The pulley 47 is mounted directly in line with the pulley 28 and a belt 49 passes thereover. The pulley 48 is mounted directly in line with pulley 43 and a belt 51 passes over these pulleys. Accordingly, when power is supplied to the motor 26 the feed rolls are driven from the shaft thereof through the belts 29, reduction gear 27, pulley 28, belt 49, pulley 47, shaft 46, pulley 48, belt 51 and the pulley 43 and web material between the rolls 38, 39 and 41, 42 would be fed therethrough and wound on the mandrel 32.

The looper exit roll 22 is driven by means of a chain 52 passing over sprocket 23, the chain being driven from the winder feed roll 39 as will be described so that there is a direct drive between the winder drive rolls and the looper exit rolls. In this manner, the relative rotative speeds of these rolls is always known and fixed, and is not subject to random variations, the ratio of these rotative speeds being fixed at any desired value. For providing a driving connection between the looper exit rolls and the winder feed rolls and for varying the speed between these groups of rolls, the synchronizing device 34 is mounted directly on the shaft 53 of and rotating with the lower winder feed roll 39. Referring to Fig. 3 it will be seen that the synchronizing device is a differential gear mechanism by means of which a component of speed may be added to or subtracted from the chain 52 driving the looper exit rolls.

The synchronizing device includes the shafts 53 and 54, the ring gear 55 and the drive gears 56, 57, 58 and 59. The ring gear 55 is mounted to rotate on the shaft 53 on a bearing including the bushing 60 and the rollers 61, the rollers

bearing directly on the shaft 53 and being held in place by means of the retainer 62. Rigidly bolted to the ring gear 55 is a yoke or bracket 63 which is spaced away from the gear 55 and extends substantially thereacross to support one end of the shaft 54, the yoke being provided with a hole through which the shaft 53 passes as shown. The outer end of the yoke 63 has an opening into which the shaft 54 is received, the rollers 64 forming the necessary bearing and the retainer 65 being provided to hold the rollers in place. The shaft 54 is prevented from moving toward the right by a washer 66 bearing against the yoke, the washer being held to the shaft 54 by the bolt 67. Keyed to shaft 53 between the yoke 63 and the gear 55 is the gear 56, and meshing with the gear 56 is the gear 57 which is keyed to the shaft 54. The shaft 54 passes through a hole in ring gear 55 and is supported therein by a bearing including the bushing 68 and the rollers 69, the rollers being held by the retainer 71. Rotatively mounted on the shaft 53 adjacent the gear 55 on the opposite side thereof to the gear 56 is the gear 58, the gear 58 being mounted on sleeve bearing 72. Meshing with gear 58 and keyed to shaft 54 is the gear 59 which is mounted against the bushing 68. The shaft 54 is held from moving toward the left by a washer 73 bearing against the gear 58 and bolted to the shaft by the bolt 74. Keyed to the gear 59 so as to rotate therewith and concentric with the shaft 53 is the toothed sprocket 75. The sprocket 75 and the gears mounted on the shaft 53 are held thereon by the collar 76 which is held to the shaft 53 by the setscrew 71.

Assuming that the ring gear is held stationary, as will be made clear, and assuming further that the shaft 53 is rotating counterclockwise (i.e., the roll 39 is rotating and the winder is in operation), the gear 56 will rotate counterclockwise since it is keyed to the shaft 53. Since the ring gear and shaft 54 are stationary, the gear 57 rotates clockwise by virtue of its meshing with gear 56. Consequently, the shaft 54 rotates in its bearings in the yoke and the ring gear and rotates the gear 58 also keyed to the shaft 54 in a clockwise direction. The rotation of the gear 58 in a clockwise direction rotates the gear 59 meshing therewith in a counterclockwise direction, and by virtue of the keyed connection between the gear 59 and the toothed sprocket 75 the toothed sprocket rotates counterclockwise. Therefore the chain 52 engaging the sprocket 75 rotates the sprocket 23 and the looper exit roll 22 counterclockwise. Thus it is seen that the looper exit rolls are driven through a nonslipping connection from the winder drive rolls and accordingly the normal ratio of the rotative speeds between these rolls may be fixed at any value and maintained thereat. The rotative speed of roll 22 relative to the rotative speed of roll 39 is determined in part by the ratio of gears 56 and 57 and the ratio of gears 58 and 59, and in part by the ratio of the sprockets 75 and 23. These ratios may be of any desired values, and in a particular case, such as between a winder and a looper of the character described, and for web material such as roofing, the ratio of gear 56 to gear 57 may be three-quarters, and the ratio of the gear 58 to the gear 59 may be unity. Therefore, the sprocket 75 rotates at three-quarters of the speed of roll 39. The sprocket 23 may have the same number of teeth as the sprocket 75, and hence the roll 22 rotates at three-quarters of the speed of the roll 39. Ordinarily the number of feet of material fed out of the exit rolls 21

and 22 are the same as the number of feet of material fed into the rolls 38 and 39. In the particular example given, for example, as one instance of use, the rotative speed of the roll 22 is three-quarters that of roll 39, and thus the diameter of the roll 22 is substantially four-thirds that of roll 39.

In the operation of the winder and looper, a slack loop 80 of material is maintained therebetween so that the winder will have sufficient material to wind without placing tension thereon. The loop becomes longer or shorter, due to conditions already pointed out, and to maintain it between desired limits the ring gear 55 of the synchronizing device 34 is arranged to be rotated in either direction.

Referring to Figs. 1 and 2, and particularly to Figs. 3 and 4, there is shown a worm gear 78 engaging the teeth of ring gear 55, the worm gear being supported in bearings 79 and 81 on the bearing bracket 82. The worm gear is coupled to the shaft of the reversible motor 83 supported on the bracket 84. The motor 83 is a three-phase alternating current motor and is reversible by reversing any two of the power leads connected to it, as will be more fully pointed out, but it will be apparent that other motors, for example direct current motors, may be used. When the motor 83 is not operating the worm gear is stationary and hence ring gear 55 is stationary, as pointed out before in this specification, for normal operation.

To explain the functioning of the synchronizing device for shortening or lengthening the loop 80, it is assumed that the roll 39 is stationary and the loop has a certain length. In the first instance it is further assumed that the loop has become short and it is necessary to lengthen it. This is accomplished by rotating the roll 22 faster than its usual speed so as to feed more material into the loop. Therefore, the sprocket 75 must rotate counterclockwise to rotate sprocket 23 counterclockwise (the sprockets are assumed stationary so far as the regular drive is concerned). Accordingly, the motor 83 must be energized to rotate the ring gear 55 counterclockwise (i. e., same as the regular rotation of the roll 39). Also for purposes of explanation, it is assumed that the ring gear has rotated one complete revolution.

After one revolution of ring gear 55, the shaft 54 and gears 57 and 58 have made one complete revolution about the shaft 53. In addition to this revolution the gear 57 has rotated about the shaft 54 three-quarters of a revolution due to its meshing with stationary gear 56 (the ratio of gears 56 and 57 is three to four). The rotation of gear 57 about shaft 54 has been counterclockwise and hence the gear 58 has rotated about the shaft 54 three-quarters of a revolution in a counterclockwise direction. If the gear 58 had been stationary so far as shaft 54 is concerned, and had been rotated around the shaft 53 by virtue of the ring gear carrying the shaft 54 around with it, the gear 59 would have made a complete revolution in a counterclockwise direction because the gears 58 and 59 would have been locked together. However, since the gear 58 is rotating around the shaft 54, the gear 59 rotates a lesser amount by the amount the gear 58 rotates. Thus since the gears 58 and 59 are of the same size and the gear 58 has rotated three-quarters of a revolution about the shaft 54, the gear 59 has rotated one-quarter of a revolution counterclockwise. Consequently, the sprocket 75 and roll 22 have ro-

5 tated one-quarter of a revolution counterclockwise and have added a number of feet of material to the loop 80 equal to the distance the circumference of roll 22 moves in one-quarter revolution. In the event it is necessary to shorten the loop 80, worm 78 is rotated in the reverse direction by the motor 83 and the sprockets 75 and 23 rotate to turn the roll 22 in a clockwise direction and thus hold back material from the loop to shorten it. In the actual operation the rolls 39 and 22 are already rotating, and rotating the gear 55, as explained, speeds up or slows down the roll 22 over an interval of time. That is, a component of speed is added to or subtracted from the speed of the roll 22.

It is contemplated by the invention that the dimensional limits of the loop be automatically governed as desired, without the intervention of an attendant. To effectuate this intention the feed chute 85 is arranged at the exit of the looper and supports three limit switches 86, 87 and 88 which control the power supply to motor 83 to control its operation and its direction of rotation. The feed chute 85 extends at an angle to the looper so that the loop of material lies thereon in its movement and due to its weight holds the operating arms of the limit switches 86 and 87 in the necessary initial positions.

Power is supplied to the motor 83 from a three-phase, sixty cycle source L₁, L₂, L₃, through a manual control box indicated by the broken line 90 and an automatic control box indicated by the broken line 91 through circuits to be described. The control box 90 includes a three contact switch 92 and the fuses 93, 94 and 95 one of which is in each of the lines L₁, L₂, and L₃, to protect the equipment in the event of a short circuit. The control box 91 includes two contactors 96 and 97 for controlling the direction of operation of the motor 83, two motor overload relays 98 and 99 and circuits interconnecting these elements and the motor.

The contactor 96 is of a well known type having the pairs of normally open contacts 101, 102 and 103, and an operating coil 104 which maintains the contacts closed only so long as the coil is energized. The contactor 97 is substantially identical to the contactor 96 and includes the pairs of normally open contacts 105, 106, and 107, and an operating coil 108 which maintains the contacts closed only so long as the coil is energized. Upon de-energizing the coils 104 and 108 the contacts operated thereby open. The overload relay 98 includes the normally closed contacts 109 and the resistor 110, the contacts being adapted to be opened by a thermally responsive element which may be the element bridging the contacts or a separate element when the temperature developed by the resistor 110 becomes too great. Similarly the overload relay 99 includes the normally closed contacts 112 and the resistor 113, the contacts being adapted to be opened by a thermally responsive element when the temperature developed by the resistor 113 becomes too great. The overload relays 98 and 99 control the power supply to coils 104 and 108 of the contactors 96 and 97 to open them when an overload occurs.

With the switch 92 closed, power will be supplied by closing the contacts 101, 102 and 103 through the following circuits to the motor 83 to operate in a direction to lengthen the loop 80: From L₁ through conductor 114, conductor 115, contacts 103, conductor 116 and conductor 117 to the motor. From L₂ through conductor 118,

conductor 119, contacts 102, conductor 121, resistor 110 and conductor 122 to the motor. From L₃ through conductor 123, conductor 124, contacts 101, conductor 125, conductor 126, resistor 113, and conductor 127 to the motor. Power is supplied to the motor 83 to operate in a direction to shorten the loop 80 through the following circuits by closing the contacts 105, 106 and 107 (the contacts 101, 102 and 103 being open). From L₁ through conductor 114, contacts 107, conductor 128, resistor 113 and conductor 127 to the motor. From L₂ through conductor 118, contacts 108, conductor 128, conductor 121, resistor 110 and conductor 122 to the motor. From L₃ through conductor 123, contacts 105 and conductor 117 to the motor. The terminal of the motor connected to L₂ remains the same in each of the described situations and the terminals of the motor connected to L₁ and L₃ are reversed thereby reversing the motor rotation as is well understood.

The coils 104 and 108 of the contactors 96 and 97 respectively are supplied through the time delay relays 130 and 131 which are in turn controlled by the limit switches 87 and 88 respectively. The relay 130 is of the well known dashpot time delay type including a pair of contacts 132, an operating coil 133 and a dashpot device 134 for delaying the opening of the contacts after they have once closed and the coil energization is removed. Similarly the relay 131 includes a pair of contacts 135, an operating coil 136 and a dashpot time delay device 137.

Referring more particularly to Fig. 7, there is shown a sectional view of a time delay relay such as relays 130 and 131 comprising a chamber 138 having a diaphragm dividing it into two parts. On one side of the diaphragm there is a poppet valve 139 covering a relatively large opening so that when the diaphragm is pushed upwardly the air in that side of the chamber is pushed out without resistance. On the same side of the diaphragm there is a needle valve 141 which is adjustable to vary the size of an opening into the chamber. Thus when the diaphragm moves downwardly the valve 139 closes the opening associated therewith and a vacuum is created on the upper side of the diaphragm. The diaphragm moves downwardly slowly as air flows into the chamber through the opening controlled by the needle valve 141. By varying the position of the needle valve, the time delay is varied. On the lower side of the diaphragm there is an operating arm 142 attached to a block 143 which is biased downwardly by a spring 144. The opening in the chamber below the diaphragm through which the arm 142 passes is sufficient in size so that relatively little resistance to the flow of air therethrough is experienced. The relay contacts are operated by a lever 150 actuated by the lug 145 on the block 143, and below the block 143 there is shown a coil 146 for initiating operation of the relay. The time delay produced is the result of the force of the spring 143 and the force of the vacuum above the diaphragm. Other means may be employed for producing a time delay such as escapement mechanisms or short-circuited windings on the relay coils, for example.

The coil 104 is energized when the relay contacts 132 are closed to pick up the contactor 96 through a circuit extending from one terminal S₁ of a source of supply, through a fuse 147, conductor 148, conductor 149, contacts 132, conductor 151, conductor 152, coil 104, conductor 153, contacts 109 and 112 in series, conductor 154, conductor 155 and fuse 156, to the other terminal S₂

of the source of supply. When the contacts 132 open the coil 104 is de-energized and the contactor 96 drops out. The coil 108 is energized when the relay contacts 135 are closed to pick up the contactor 97 through a circuit extending from S₁, through fuse 141, conductor 148, conductor 157, contacts 135, conductor 158, conductor 159, through coil 108, conductor 161, conductor 153, contacts 109 and 112 in series, conductors 154 and 155 and fuse 156 to S₂. Whenever the contacts 135 open, the coil 108 becomes de-energized and the contactor 97 drops out.

The coil 133 of the relay 130 is energized through a circuit extending from S₁, through conductor 148, conductor 162, contacts of limit switch 86, conductor 163, contacts of limit switch 87, conductor 164, coil 133, conductor 165 and conductor 155 to S₂. The coil 136 of the relay is energized through a circuit extending from S₁, through conductor 148, conductor 162, contacts of limit switch 86, conductor 163, conductor 166, contacts of limit switch 88, conductor 167, coil 136, conductor 168 and conductor 155 to S₂.

Referring to Fig. 6, an elementary wiring diagram, it will be seen that the contacts of limit switch 86 are in series with the contacts of the limit switches 87 and 88. Consequently neither of the relays 130 and 131 may be energized when the limit switch 86 is open, i. e., there is no loop at all between the looper and the winder.

In the normal operation of the looper, winder and synchronizing device, the rolls 39 and 22 are rotating, the loop 80 is maintained about at the position 80b and can move between the positions 80a and 80c before the synchronizer comes into operation. Normally when the loop is lying with one side on the chute 85 with its lower end at 80b and the contacts of the limit switch 86 are closed, the contacts of the limit switches 87 and 88 are open. Referring particularly to Figs. 1 and 6, if the loop shortens to a point above the position 80a due to whatever cause, such as slipping of the material in the rolls, for example, the material uncovers the arm of the limit switch 87 which closes its contacts and energizes the coil 133 of relay 130 through the described circuit, the limit switch 86 being closed whenever the loop extends more than a short distance downwardly. The contacts 132 close, energizing the coil 104 to pick up contactor 96 and thereby energizing the motor 83 to effect operation of the synchronizing device to lengthen the loop as explained. As the loop lengthens by speeding up the roll 22 gradually, the loop comes into contact with the operating arm of the limit switch 87 and opens the contacts thereof, thereby de-energizing the coil 133. However, due to the time delay in the relay 130, the contacts 132 remain closed for an interval thereby permitting the synchronizing device to continue lengthening the loop. The time delay in the relay 130 may be so adjusted that for ordinary conditions encountered the loop will lengthen to position 80b before the synchronizing device stops by the contacts 132 opening. If, while operating, the motor 83 is overloaded, either or both of the contacts 109 or 112 will open due to the resistors 110 and 113 becoming hot and will de-energize the coil 132 if this has not already occurred and the motor 83 will stop at the end of the time delay interval.

If the loop lengthens out to a position at or beyond the position 80c, the web material contacts the operating arm of the limit switch 88, closing the contacts thereof and energizing the coil 136 of the relay 131 through circuits already

described. This energizes the coil 108 to pick up contactor 97 and energize the motor 83 which runs in the opposite direction to operate the synchronizing device to take material out of the loop as previously explained. As the loop shortens, the operating arm of the limit switch 88 is released, opens the contacts thereof and de-energizes the coil 136. The contacts 135 remain closed for an interval due to the time delay in the relay 131. The delay in the relay may be so adjusted that the loop shortens to the position 80b for ordinary conditions encountered before the contacts 135 open and effect stopping of the synchronizing device. In this case also if the motor 83 becomes overheated, the thermal overload relays 98 and 99 open their contacts 109 and 112 to de-energize the coil 136 if this has not occurred to stop the motor at the end of the time interval.

It may be desirable to vary the amount of material in the loop 80 while the winder 10 is stationary. This may be accomplished by manually actuating either the limit switch 87 or the limit switch 88. Thus if the contacts of limit switch 87 are manually closed, the motor 83 will be energized and will rotate the ring gear 55 in a counterclockwise direction. As already explained, when the ring gear 55 rotates counterclockwise, even though the drive roll 39 is stationary, the looper exit roll 22 will be rotated to feed material into the loop. If it is desired to shorten the loop 80, the contacts of the limit switch 88 may be manually closed which will effect energization of the motor 83 as explained to rotate the ring gear 55 in the clockwise direction to effect feeding of material into the loop to lengthen it even though the winder is stationary.

Thus the loop is shortened or lengthened in a progressive manner without rapid accelerations or decelerations of heavy rolls but by slowly and uniformly increasing or decreasing the speed of the looper exit rolls without the ministrations of an attendant.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. In a coating machine for making roofing felt including a looper for freshly impregnated roofing felt and means for feeding said felt to a winding reel, the improvement which comprises the combination of means for positively driving said feeding means, means intermediate said looper and feeding means for forming a downwardly dependent slack loop of roofing felt, said means comprising a roller for impelling roofing felt into said slack loop, a differential gear and driving means connecting said feeding means and said impelling roller, means for angularly supporting one side of said slack loop, a plurality of spaced contact switches on said supporting means actuatable by contact with said supported side of said slack loop, and a motor controlled by said switches for operating said differential gear whereby to control the speeds of said impelling roller to vary the length of the roofing felt in said slack loop.

2. The improvement as claimed in claim 1 in which there are three switches on the loop-supporting means so arranged that at the desired position of the bottom of the loop the two upper switches have their operating arms in contact with the roofing felt.

3. The improvement as claimed in claim 1 in which there are three switches on the loop-supporting means, the operating arm of the uppermost switch being always in contact with the roofing felt irrespective of contact of said felt with the operating arms of the other two switches.

4. The improvement as claimed in claim 1 in which the impelling roller is connected with the differential by means of sprocket chains and sprocket wheels.

DONALD A. CUMFER.
